UNITED STATES PATENT OFFICE.

HARVEY J. GRABER, OF KITCHENER, ONTARIO, CANADA.

CUSHION SOLE.

Application filed December 12, 1923. Serial No. 680,204.

To all whom it may concern:

Be it known that I, HARVEY J. GRABER, a subject of the King of Great Britain, and resident of the city of Kitchener, in the Province of Ontario and Dominion of Canada, have invented certain new and useful Improvements in Cushion Soles, of which the following is a full, clear, and exact description.

10 This invention relates to new and useful improvements in footwear, and the object of the invention is to provide a shoe or slipper which will have a simply constructed and inexpensively manufactured cushioned sole.

Another object is to provide a shoe or slipper which will give a comfortable and easy feeling to the sole of the foot of the wearer.

20 In my invention, I provide a shoe or slipper having a felt upper and insole, to which is attached a leather welt by means of chain stitching. A felt pad is placed between the inner edges of the welt and extends across the width of the insole. A leather sole is then stitched to the leather welt after the sole is cemented to the welt and felt pad.

In the drawings which illustrate the invention;

30 Figure 1 is a perspective view of a slipper with a part broken away to disclose the construction of the sole.

Figure 2 is a sectional elevation taken on the line 2—2, Figure 1.

35 Referring more particularly to the drawings, 11 designates the upper of a felt slipper and 12 the insole, which are stitched together. A leather welt 13 is sewn to the upper by means of chain stitching 14. The 40 welt is adapted to extend beyond the edge of the upper, said extension being desig-

nated 15. A felt pad or cushion 16 extends across the sole between the inside edges of the welt. A leather sole 17 is cemented to the welt and to the cushion and sewn to 45 the welt extension 15 by the stitches 18. A heel portion 19 may then be attached to the sole, or it may be stitched to the welt by means of the stitches 18.

The device is very simple in construction 50 and provides an easily and inexpensively manufactured type of cushioned sole. It also provides an easy and comfortable sole. In the specification I have specified a leather sole, but rubber or any other material may 55 be used for the sole of the shoe or slipper without departing from the spirit of the invention.

Having thus described my invention, what I claim is;—

60 An article of footwear comprising an upper having inturned bottom edges, an insole having inturned bottom edges coinciding with the edges of the upper and resting upon the latter, a narrow leather welt, underlying the upper with its inner edges coinciding with the edges of the upper and the insole, a row of vertical stitching joining the upper, insole and welt near said edges, a felt cushion fitted snugly in the 65 space bounded by the edges of the upper, welt and insole, and underlying the latter, and an outer sole cemented to the welt and to the underside of the cushion and a row of vertical stitching passing through the 70 welt and outsole and positioned between the wall of the upper and the outer edge of the welt.

75 In witness whereof, I have hereunto set my hand.

HARVEY J. GRABER.
